UNITED STATES PATENT OFFICE

GEORGE W. VOS, OF NEW ROCHELLE, NEW YORK

DESIGN FOR A GASOLINE DISPENSING PUMP

Application filed June 16, 1932. Serial No. 44,093. Term of patent 14 years.

To all whom it may concern:

Be it known that I, GEORGE W. Vos, a citizen of the United States, residing at No. 28 Pershing Avenue, in the city of New Rochelle, county of Westchester, and State of New York, have invented a new, original, and ornamental Design for Gasoline Dispensing Pump, of which the following is a specification, reference being had to the accompanying drawing, forming part thereof.

Figure 1 is a view in front elevation of a gasoline dispensing pump embodying my design, and Figure 2 is a top plan view of the same.

I claim:

The ornamental design for a gasoline dispensing pump, as shown.
